[57] CLAIM

The ornamental design for an eyewear front, as shown and described.

DESCRIPTION

FIG. 1 is a front, elevational view of an eyewear showing my new design;

FIG. 2 is a side, elevational view thereof;

FIG. 3 is a rear, elevational view thereof;

FIG. 4 is a top plan view thereof;

FIG. 5 is a bottom plan view thereof; and,

FIG. 6 is a front perspective view thereof.

The dashed lines appearing in the Figures are for environmental purposes only and as such form no part of the claimed design.
